(57) **CLAIM**

The ornamental design for a game board and game pieces, as shown and described.

DESCRIPTION

FIG. 1 is a top perspective view of the game board component shown separately for clarity of illustration;

FIG. 2 is a top view of the game board of FIG. 1; FIG. 3 is a bottom view of the game board of FIG. 1; FIG. 4 is a front elevational view of the game board of FIG. 1; FIG. 5 is a rear elevational view of the game board of FIG. 1; FIG. 6 is a right side of the game board of FIG. 1; FIG. 7 is a left side of the game board of FIG. 1; FIG. 8 is a top perspective view of a game piece, shown separately for clarity of illustration; FIG. 9 is a front elevational view of the game piece of FIG. 8; FIG. 10 is a rear elevational view of the game piece of FIG. 8; FIG. 11 is a right side view of the game piece of FIG. 8; FIG. 12 is a left side view of the game piece of FIG. 8; FIG. 13 is a top view of the game piece of FIG. 8; FIG. 14 is a bottom view of the game piece of FIG. 8; FIG. 15 is a top perspective view of a game piece, shown separately for clarity of illustration; FIG. 16 is a front elevational view of the game piece of FIG. 15; FIG. 17 is a rear elevational view of the game piece of FIG. 15; FIG. 18 is a right side view of the game piece of FIG. 15; FIG. 19 is a left side view of the game piece of FIG. 15; FIG. 20 is a top view of the game piece of FIG. 15; FIG. 21 is a bottom view of the game piece of FIG. 15; FIG. 22 is a top perspective view of a game piece, shown separately for clarity of illustration; FIG. 23 is a front elevational view of the game piece of FIG. 22; FIG. 24 is a rear elevational view of the game piece of FIG. 22; FIG. 25 is a left side view of the game piece of FIG. 22; FIG. 26 is a right side view of the game piece of FIG. 22; FIG. 27 is a top view of the game piece of FIG. 22; FIG. 28 is a bottom view of the game piece of FIG. 22; and, FIG. 29 is a top perspective view of the game board and game pieces in accordance with our new design.

The evenly-dashed broken lines in the drawings illustrate the portions of the game pieces and game board that form no part of the claim.

1 Claim, 20 Drawing Sheets
